UNITED STATES PATENT OFFICE.

WILLIAM H. SAUVAGE, OF FLUSHING, NEW YORK, ASSIGNOR, BY MESNE ASSIGNMENTS, TO GOULD COUPLER COMPANY, OF NEW YORK, N. Y.

SLACK ADJUSTER.

1,414,671.

Specification of Letters Patent. Patented May 2, 1922.

Application filed February 6, 1920. Serial No. 356,751.

To all whom it may concern:

Be it known that I, WILLIAM H. SAUVAGE, a citizen of the United States, residing at Flushing, Long Island, in the county of 5 Queens and State of New York, have invented certain new and useful Improvements in Slack Adjusters, of which the following is a specification.

This invention relates to improvements in 10 railway slack adjusters and more particularly to what is known as take-up holding means adapted to operate on release of the brakes whereby the excess slack is taken up in the brake rigging.

15 One of the objects of the present invention is to provide a simple and practical take-up and holding means having relatively few parts which may be inexpensively manufactured and assembled.

20 A second object is to provide a take-up and holding means of the above general character and applicable to practically any form of slack adjuster mechanism involving two relatively movable parts adapted to be 25 held in their new relation.

A further object is to provide take-up and holding means which may be easily released to permit a readjustment of the brake rigging as is necessary when applying new 30 brake shoes or parts to the brake rigging.

A further object is to provide a strong and substantial structure which will not be affected by the atmospheric conditions and of which there is little or no danger 35 of the parts rusting into a set position thereby to interfere with the proper manipulation or operation of the device.

With these and other objects which will 40 appear obvious from the following description, attention is directed to the annexed sheets of drawings forming part of this specification wherein corresponding and reference characters denote similar parts.

In these drawings Figure 1 is an elevational view showing one application of the take-up mechanism to one type of slack adjuster.

Figure 2 is an end view, and,

Figure 3 is a sectional plan view.

50 Referring now to Figures 1 and 2, 5 denotes the live lever of the truck brake rigging which is adapted to be secured to the brake beam by means of strut 6. The lower end of the live lever is pivotally connected

at 7 to one end 8 of a telescopic push 55 rod. This rod telescopes with a tubular member 10, Figure 3, the opposite end of which is adapted to be connected with the lower end of the dead lever not shown.

Pivotedly connected with the strut 6 by 60 a lost motion connection 11 is an adjusting rod 12 which also passes downwardly through a portion of or lugs on the telescopic member 10. By reference to Figure 65 3 of the drawings it will be seen that the take-up and holding mechanism comprises a housing 13 formed at the outer or free end of the tubular member 10 and contains a plurality of holding dogs 14.

In the present case these dogs are 70 rectangular pieces of sheet metal through which are holes provided with case hardened or tempered edges 15 adapted to embrace and bite into the rod 8 when it is attempted to be moved in a relatively left hand direction. 75 These dogs 14 are preferably held in canted relation by means of a coil spring 16 acting between one of the dogs 14 and the adjacent end wall 17 of the housing 13.

At one side of the housing 13 are two 80 lugs 18 adapted to support the adjusting rod 12 and guide the same in its relative movement in a direction substantially parallel to the rod 8. A second set of dogs (only one however is indicated at 20) is 85 fulcrumed at 21 and is provided with a slightly larger opening 22 adapted to permit free passage of the rod 8 in either direction. There is, also, provided an additional hole 23 adapted to embrace and coact with 90 the adjusting rod 12 in the manner. The dog or dogs 20 is also held in inclined or canted position by means of a coiled spring 24 acting between the dog 20 and the stop 25. By moving the extending end of the 95 dog 20 relatively towards the right all of the dogs 14 as well as the dog 20 will be moved to a parallel position the dog 14 at the right resting against a stop 25 in which position all the dogs 14 and 20 lie normal to 100 the rods 8 and 12 thereby permitting a free movement of either rod in either direction as may be necessary. The operation of this device is substantially as follows:—

When the brakes are applied the upper 105 end of the live lever moves relatively towards the right to apply the brakes carried by the strut 6. The reaction takes place

through the holding rods 8 and 12 which are prevented from relative telescopic movement toward the left by reason of the dogs 14 and 20. If excess travel takes place the 5 adjusting rod 12 is moved relatively towards the right and slides through the opening 23 in the dog 20 an amount corresponding exactly to the excess travel.

When the pressures are released, however, 10 this adjusting rod 12 is held against movement towards the left by reason of the canting engagement of the edges of the hole 23 with the rod. The pivot 11 then becomes a fulcrum point during the return of the 15 live lever 5 to full release position thereby to move the rod 8 relatively outward or towards the right which movement is permitted of the construction of the dogs. The full return of the live lever will insure the 20 outward movement of the rod 8 an amount exactly corresponding to the outward movement of the rod 12 during the application of the brakes thus taking up practically all of the slack at a single operation.

25 From the above it will be seen that the present structure does away with any frictional devices which might tend to rust and set thereby preventing a proper operation of the brakes. The structure is simple, practicable and durable involving few parts inexpensive to manufacture, and which may be assembled and readjusted as may be necessary on applying new brake shoes.

It is believed that the above will so fully 35 reveal the gist of the present invention that others can by applying current knowledge readily adapt the same to various uses and modifications, and the appended claims are intended to cover all of the generic and 40 specific features thereof that may be comprehended within the range of equivalency.

What I claim is:—

1. In a slack adjuster, in combination, a 45 two-part telescopic push rod, a housing formed on one of said parts, a plurality of dogs therein adapted to coact with the other of said parts and an adjusting rod, one of said dogs being provided with two openings through which the adjusting rod and one 50 part of the push rod are adapted to pass.

2. In a slack adjuster, in combination, a 55 two part telescopic push rod including a rod and a tubular member, a housing formed on the tubular member, a plurality of dogs carried thereby adapted to coact with the rod, an adjusting rod supported parallel to said first mentioned rod, and means in the housing for supporting said adjusting rod.

3. In a slack adjuster, in combination, a 60 two part telescopic push rod including a rod and a tubular member, a housing formed on the tubular member, a plurality of dogs carried thereby adapted to coact with the rod, an adjusting rod parallel to said first mentioned rod and means on the housing

for supporting said adjusting rod, one of said dogs coacting with both the push rod and the adjusting rod.

4. In a slack adjuster, in combination, a two part telescopic push rod including a rod 70 and a tubular member, a housing formed on the tubular member, a plurality of dogs carried thereby adapted to coact with the rod, an adjusting rod parallel to said first mentioned rod and means on the housing for 75 supporting said adjusting rod, one of said dogs coacting with both the push rod and the adjusting rod, said housing having a fulcrum for said last mentioned dog whereby when it is moved to a position normal to the adjusting rod all of said dogs will be moved to a parallel position.

5. In a slack adjuster, in combination, a two part telescopic push rod including a rod and a tubular member connected therewith, 85 a housing associated with the tubular member having two fulcrums, two sets of dogs within said housing coacting with said rod and an adjusting rod associated therewith with which the other set of dogs coact.

6. In a slack adjuster, in combination, a two part telescopic push rod including a rod and a tubular member connected therewith, a housing associated with the tubular member having two fulcrums, two sets of dogs 95 within said housing one of which coacts with said rod, an adjusting rod associated therewith with which the other set of dogs coact, and springs normally holding said dogs in canted position.

7. In a slack adjuster, in combination, a two part telescopic push rod including a rod and a tubular member connected therewith, a housing associated with the tubular member having two fulcrums, two sets of dogs 105 within said housing coacting with said rod, and an adjusting rod associated therewith with which one set of dogs only coact, and a spring associated with each set of dogs adapted to hold the same in canted position.

8. In a slack adjuster, in combination, a two part telescopic push rod including a rod and a tubular member connected therewith, a housing associated with the tubular member having two fulcrums, two sets of dogs 115 within said housing one of which coacts with said rod, and the other, with an adjusting rod associated therewith, a spring on said adjusting rod coacting with one dog and a spring on the push rod coacting with the other dog whereby said dogs are held in 120 canted relation.

9. In a slack adjuster in combination, a two part telescopic push rod including a rod and a tubular member connected therewith, a housing associated with the tubular member having two fulcrums, two dogs within said housing coacting with said rod, and an adjusting rod associated therewith with which the other dog coacts, a spring on said 125 130

adjusting rod coacting with one dog and a spring on the push rod coacting with the other dog whereby said dogs are held in canted relation, and means whereby movement of one dog will move the other dog into a position at right angles to the rods against the compression of said springs.

- 10 10. In a slack adjuster, in combination, a telescopic push rod comprising a tubular member and a rod telescoping therewith, a housing formed on said tubular member, perforated lugs on said housing, an adjusting rod passing through said lugs and lying substantially parallel to said first mentioned 25
15 rod, and a plurality of dogs within said housing coacting with said first mentioned rod, one of said dogs engaging also the adjusting rod, and means for holding said dogs in inclined position.
- 20 11. In a slack adjuster, in combination, a telescopic push rod comprising a tubular

member and a rod telescoping therewith, a housing formed on said tubular member, perforated lugs on said housing, an adjusting rod passing through said lugs and lying substantially parallel to said first mentioned rod, a plurality of dogs within said housing coacting with said first mentioned rod, one of said dogs engaging also the adjusting rod, and means for holding said dogs in inclined 30 position, said dogs being so positioned and arranged that a movement of the dog engaging both rods to a position at right angles to the rods will move the other dog to a position parallel thereto.

35 In testimony whereof I affix my signature in the presence of two witnesses.

WILLIAM H. SAUVAGE.
